UNITED STATES PATENT OFFICE.

ARTEMAS E. F. HOLDEN, OF CENTRALIA, WEST VIRGINIA.

CHURN-DASHER.

1,296,663.

Specification of Letters Patent. Patented Mar. 11, 1919.

Application filed February 23, 1918. Serial No. 218,831.

To all whom it may concern:

Be it known that I, ARTEMAS E. F. HOLDEN, a citizen of the United States, residing at Centralia, in the county of Braxton and State of West Virginia, have invented new and useful Improvements in Churn-Dashers, of which the following is a specification.

This invention relates to churn dashers and is an improvement on a patent granted to me May 15, 1917, Serial No. 1,226,518.

As in the above named patent, the object of the present invention is to provide a dasher formed of a single piece of material in the form of a disk, adapted to be applied to the dasher staff or a churn and which operates in the liquid as the staff is reciprocated vertically to thoroughly and effectually agitate the same, whereby the globules of oil are ruptured and the particles of fat quickly liberated.

To accomplish this, the dasher is made from a sheet of metal preferably in the form of a disk, having its central and peripheral portions lying in the same plane, the same portions being connected together by radially disposed intermediate portions, there being provided at the edges of the said radially disposed intermediate portions upwardly and downwardly extending wings or blades pitched at acute angles with relation to the plane in which the central and peripheral portions lie. The said central portion is provided with arcuate incisions and the material at the inner edges is formed in semi-conical configuration thereby forming hoods with openings at their outer or larger ends. Each alternate hood is disposed above the plane in which the central portion of the disk lies and the other hoods are disposed below said plane.

It has been found in practice, that a dasher so constructed has a tendency to rotate, due to the inclination of the angularly disposed blades or wings and it is object of the present invention to overcome or reduce this tendency, in order to premit of a truly or nearly vertical movement of the dasher, so as to direct the material passing therethrough at an angle for proper mixture. This is accomplished by forming openings in the horizontal surface of the disk for the passage of the material acted upon through these openings, the material thereby forming a vertical column or stream, which resists this rotary tendency. These openings

are so shaped as to coöperate with the openings between the angular wings to direct the material toward the outer periphery of the disk, to cause the broken particles to commingle.

In the drawings:

Figure 1 is a plan view of the dasher; Fig. 2 is a side view of the dasher secured upon the end of the dasher staff;

Fig. 3 is a detailed sectional view on the line 3—3 of Fig. 1;

Fig. 4 is a similar view on the line 4—4 of Fig. 1;

Fig. 5 is a view similar to Fig. 4 showing the oppositely disposed hood, this figure being taken on the line 5—5 of Fig. 1;

Fig. 6 is a fragmentary sectional view showing one manner of mounting the dasher upon the staff; and

Fig. 7 is a detail perspective view of a portion of the dasher showing a modified form of blades or wings.

Referring to the drawings in detail, the dasher comprises a disk 1 which is preferably circular in plan and which is formed of a single sheet of metal. The disk includes a central portion 2 and a peripheral portion 3, the said portions lying in the same plane and being connected by radially disposed portions 4, which also lie in the same plane. The portions 4 are provided at one edge with downwardly disposed wings or blades 5 and at their opposite edges with upwardly disposed wings or blades 6, to form an angularly disposed passage for the liquid. The intermediate portion is provided with a series of spaced arcuate incisions 7 and the material of the said portions 1 at the inner edges of these incisions is formed into semi-conical hoods 8, the larger ends of which are outwardly disposed to provide additional passages for the liquid.

Each alternate hood 8 is disposed above the plane in which the central portion 2 lies and the other hoods are disposed below said plane. The dasher and dasher staff are intended for use in a churn body of any usual configuration and the said dasher may be either loosely mounted or fixed upon the staff.

Upon the downward stroke of the staff, those hoods 8 which are disposed above the plane of the central portion 2 will have a tendency to force the liquid outwardly and radially and upon the upward stroke the hoods 8 which are disposed below the plane

will have the same effect upon the liquid. In the event of the dasher being loosely mounted upon the staff, the passage of the liquid through the openings between the 5 wings or blades 5 and 6 will tend to rotate the dasher.

In order to check this tendency, the portions 3 are provided with openings 10 and 11, the former being preferably circular, 10 while the latter are radially disposed elongated tapered openings, the restricted portions of said openings being disposed toward the axis of the disk. These openings 10 and 11 provide for the passage of a vertical column 15 of the liquid, which acts against the column passing through the angularly disposed passage to counteract the tendency of the latter column to rotate the disk. In addition the restricted inner ends of the openings 11 cause the liquid to pass through at this point with more force than at the opposite larger ends of the openings, so that the column of liquid passing therethrough will be directed toward the periphery of the disk, 20 coöperating to thoroughly mix the liquid, and to cause more rapid separation of the butter fat.

In Fig. 7 is shown a modified form of the invention, in which the blades or wings 30 are arranged in paths along each edge of the

portions 3, the said blades extending upwardly and downwardly and being disposed at an acute angle, the upper blades being designated by the reference character 12, while the lower blades are shown at 13. 35 This construction provides oppositely disposed angularly passages along each edge of the portions 3, one passage tending to counteract the rotary effect of the adjacent passage. 40

Having described the invention, what is claimed is:—

A churn dasher comprising a disk having central, peripheral and radially disposed portions lying in the same plane, said 45 radially disposed portions having openings therein, oppositely arranged angularly disposed blades provided along each edge of the radially disposed portions, said blades being arranged in radially alined 50 pairs and extending in opposite directions to form opposite angularly disposed passages between each of the radially disposed portions and cone shaped hoods provided upon the central portion and disposed some above 55 and others below the plane thereof, the larger ends of the hoods being disposed outwardly and open.

In testimony whereof I affix my signature.
ARTEMAS E. F. HOLDEN.
